RIFLE BOLT

Filed April 4, 1923

Inventor,
Jose Valero

Attorneys

UNITED STATES PATENT OFFICE.

JOSE VALERO, OF MONTEREY, MEXICO.

RIFLE BOLT.

Application filed April 4, 1923. Serial No. 629,900.

To all whom it may concern:

Be it known that I, JOSE VALERO, a citizen of Mexico, residing in Monterey, Nuevo Leon, Mexico, have invented certain new and useful Improvements in Rifle Bolts, for which the following is a full and complete specification, reference being had to the accompanying drawing.

This invention relates to new and useful improvements in rifle bolts and in particular to those adapted to or forming part of rifles of the Mauser type. It is an object of the invention to provide a rifle bolt of maximum efficiency, simplicity of construction and also less liable to damage from wear or rough treatment.

More particularly, my invention deals with a striker-bar and its associated striking pin so designed as to permit the replacement of the latter when occasion demands without entailing the replacement or readjustment of other parts of the bolt mechanism.

Furthermore, the design hereinafter more fully described permits of greater ease in cocking the striker in the event the same is necessary due to defective ammunition and where it is undesirable to move the bolt itself.

For convenience of assembly and taking apart, a rifle bolt which includes these improvements will be found to have material advantages over those of the conventional type, as there will be no requirement for the exertion of considerable force, nor the overcoming of the friction of the parts nor the use of the parts from the device itself as instrumentalities in the disassembly.

For purposes of illustration and as showing one form in which my invention may be embodied, in the drawings:

Fig. 1 is a plan view of a rifle bolt;

Fig. 2 is a plan view of the striker-bar and striker;

Fig. 3 is a vertical elevation of one end of the mechanism, part of which is shown in vertical section on line 3, 3 of Fig. 1;

Fig. 4 is a vertical section taken on the line 4, 4 of Fig. 1;

Fig. 5 is an elevation taken on the line 5, 5 in Fig. 1;

Fig. 6 is a side view of the front head piece with the associated striker-bar; and

Fig. 7 is a side view of the striker.

I have shown my invention as adapted to the conventional cylindrical bolt of the

Mauser type shown generally by numeral 11, in the accompanying drawings. This bolt has the customary side lug 12 and operating lever 13. Immediately in the rear of the lever 13 the bolt has a reduced end 14 with an abutting edge 15 between the two diameters. As shown in Fig. 3, the upper surface of the reduced portion 14 carries the transverse groove 16 which receives the locking portion of the safety catch.

A cocking sleeve 17 of hollow construction is journalled upon the reduced portion 14 and has a forward cam shaped end 18, which cooperates with the lever 13 during the operation of cocking. This cocking sleeve 17 has on its lower face a detent or lug 19 which is held and released by the sear of the rifle in the customary manner. In the rear of the detent 19 the sleeve is recessed as at 20 to receive the cocking piece as will later appear. The upper portion of the sleeve has two upstanding ears 21, 22, the intermediate space being open above the recess 16 in the reduced end of the sleeve 11. The safety catch lever 23 extends between the ears 21 and 22 and has a lowermost portion 24 extending into the recess 16 when in the "safe" position but riding over the reduced end 14 in the "ready" position. The upper portion of the sleeve is drilled to provide the longitudinal chamber 25 which carries the pivot pin 26 extending forwardly through the ears 22 and 21 and the intervening catch 24. A spring 27 extends between a shoulder on the pin 26 and the opposite ear 22. The upper portion of the pin 26 is grooved to receive the end of the adjusting screw 28 which limits the reciprocation of the pin 26 under the influence of the spring 27. The screw 28 permits the movement of the pin 26 to the rear so that the latter may project slightly beyond the rear wall of the sleeve 17 and form a lock for the cocking piece 29.

The cocking piece, as shown in Figs. 3 and 4, is of the usual form having an enlarged end 30, a recess 31 on the front face and a forwardly and upwardly extending toe 32. The toe is adapted to slide in a groove in the lower wall of the sleeve 17 and then in a circumferential recess 20 to form a bayonet joint of about 45°. The movement of the cocking piece brings the recess 31 opposite the spring held pin 26 resulting in the latter entering the recess and locking the cocking piece against accidental removal.

The cocking piece 29 is drilled axially as

at 33 and contains enlarged recesses 34 which receive the end of the striker bar.

Carried centrally in the bolt 11 is the striker bar 35. This bar has at one end a reduced portion 36 with lateral enlargements 37. The reduced end 36 is carried within the recess 33 of the cocking piece to which it is locked by means of the enlargements 37 in the manner shown in Figs. 3 10 and 4. The opposite end of the striker bar carries a flange 38 against which spring 39 presses.

The spring 39 is held under tension against an interior flange of the receiver 11 15 in the usual manner. On the striker bar 35 and in advance of flange 38 is a flattened blade 40 in which is a slot terminating in a semi-circular or enlarged cross slot as shown in Fig. 2. The firing pin as shown in Fig. 20 7 consists of a member 41 having one end enlarged to a cross section 42 enlarged to correspond with the semi-circular slot in the chamber 40. The opposite end of the pin is tapered as shown.

25 The forward end of the bolt has two up-standing ears 43 and a corresponding diametrically positioned ear 44. This is shown more particularly in Fig. 5 which likewise illustrates the side grooves 45. The extractor head 46 is shown in Fig. 6 to be carried on the flat blade 40 of the striker bar, with the firing pin 41 projecting through the end of the extractor head. The extractor head has opposed locking lugs 47 30 35 which are received in the grooves 45 of the bolt and locked therein by means of angular movement.

40 The exposed face of the extractor head has a peripheral flange 48 and circumferential flange 49 of the usual type and including a spring held extracting finger, not shown.

45 It will be apparent that this bolt mechanism is assembled by sliding the sleeve 16 over the reduced end 14 of the receiver 11 and locking the two together by means of the safety member 23. The striker bar 35 surrounded by spring 39 and carrying on its end 40 the extractor head 46 is inserted 50 through the forward end of the receiver 11. In this position the end 36 projects in the rear of the reduced portion 14 and receives the cocking piece 29. Rotation of the latter serves to lock the striker bar in the cocking 55 piece 29 in the manner previously described. At the same time rotation of the extractor head 46 will have locked the same inside the receiver by means of the lugs 47.

60 With the safety member 23 in the "ready" position, the cocking piece may be retracted

by the operator. This movement constrains the sleeve 17 to move back with the toe 32. It will be obvious that a similar result is obtained by lifting and lowering the handle 13. The backward movement of the cocking 65 piece 29 draws back the striker bar 35 and pin 41 against the force of the spring 39, the member 40 sliding within the slotted channel of the extractor head 46. In its retracted position the cocking sleeve 17 and 70 the associated parts are firmly held by detent 19 against the sear of the rifle until the latter is released by the trigger.

75 It will be apparent from the above description that a rifle bolt constructed as described will be of great efficiency, simple in detail and durable under severe operating conditions. Likewise, the firing pin or striker may be readily removed and replaced in case of damage. The construction specified is well adapted for ease and speed of use. While I have described one form in which my invention may take, it will be evident that numerous changes in minor 80 details may be made without departing from 85 the scope of the claims.

What I claim as my invention is:

1. In a rifle bolt mechanism, including a bolt proper, a striker bar therein and having its rear end extending beyond the bolt, a sleeve journaled on the bolt, a safety lock connecting the sleeve with the bolt, a cocking piece carried by the end of the striker bar in contact with the sleeve and a pivot pin for the safety lock and adapted to prevent relative movement of the cocking piece with respect to the sleeve. 90

2. In a rifle bolt mechanism, including a bolt proper, a striker bar therein and having its rear end extending beyond the bolt, a sleeve journaled on the bolt, a safety lock connecting the sleeve with the bolt, a cocking piece carried by the end of the striker bar in contact with the sleeve, and a spring held pivot pin for the safety lock adapted to prevent relative movement of the cocking piece with respect to the sleeve. 100

3. In a rifle bolt mechanism including a bolt proper, a striker bar therein and having its rear end extending beyond the bolt, a sleeve journaled on the bolt, a cocking piece carried by the end of the striker bar in contact with the sleeve, a pivot pin journaled in the sleeve, and a safety lock on said pin, said lock movable to lock against a recessed portion of the bolt. 105 110 115

In testimony whereof, I have hereunto affixed my signature.

JOSÉ VALERO.
